G. W. CONWAY,
RESILIENT WHEEL.
APPLICATION FILED SEPT. 2, 1916.

1,296,925.

Patented Mar. 11, 1919.

Fig. I.

5 Fig. 2.

Inventor:

George W. Lanyay,

UNITED STATES PATENT OFFICE.

GEORGE W. CONWAY, OF NEWARK, NEW JERSEY.

RESILIENT WHEEL.

1,296,925.

Specification of Letters Patent. Patented Mar. 11, 1919.

Application filed September 2, 1916. Serial No. 118,308.

To all whom it may concern:

Be it known that I, GEORGE W. CONWAY, a citizen of the United States, residing at Newark, in the county of Essex and State 5 of New Jersey, have invented certain new and useful Improvements in Resilient Wheels; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention has reference, generally, to improvements in wheels for vehicles; and, the invention relates, more particularly, to a novel wheel of the resilient type which is especially adapted for use with 20 automobiles and similar vehicles.

The present invention has for its principal object to provide a resilient vehicle-wheel of the general construction herein-after more fully set forth, with a view of 25 providing the periphery of the main wheel-body with a number of independently movable and spring-supported tread-members or elements, each element being arranged and supported in such a manner so that the 30 tread-member or element is capable of a movement in a direction toward the center of the wheel-body.

The invention has for its further objects to provide a resilient vehicle-wheel, which 35 is perfect and efficient in its operation, the durability of which is greatly increased, and the various parts of which are readily assembled, and may be easily interchanged or replaced when necessary.

40 Other objects of the present invention not at this time more particularly enumerated will be clearly understood from the following detailed description of the invention.

With the various objects of the present 45 invention in view, the said invention consists, primarily, in the novel vehicle-wheel hereinafter set forth; and, the invention consists, furthermore, in the novel arrangements and combinations of the several de- 50 vices and parts, as well as in the details of the construction of the said parts, all of which will be more fully described in the following specification and then finally embodied in the clauses of the claim which are 55 appended to and which form an essential part of the said specification.

The invention is illustrated in the accompanying drawings, in which:-

Figure 1 is a view of a resilient vehicle-wheel, partly in side elevation and partly in 60 longitudinal vertical section, showing one embodiment of the principles of the present invention; and Fig. 2 is a detail transverse vertical section of the same, said section being taken on line 2-2 in said Fig. 1. 65

Similar characters of reference are employed in all of the said above described views, to indicate corresponding parts.

Referring now to the said figures of the drawings, the reference-character 1 indicates a ring-like element of any suitable diameter and width, the said element being provided with laterally extending holes, as 2, in which are disposed tie-bolts or rivets as 3. Suitably secured by means of the 70 said bolts or rivets upon the opposite side-faces 4 and 5 of the said ring-like element 1 are a pair of circular members or elements 6, said members or elements being provided with a series of 75 spokes 7 radiating from central portions 8, and each portion 8 being provided with a suitable opening 9 for the reception of a bearing or the end of an axle, as will be clearly evident. The outer marginal edge- 80 portions 10 of the said circular members or elements 6 extend suitably beyond the outer cylindrical surface 11 of the said ring-like element 1, so as to provide an outer annular receiving space, as 12. In its said outer 85 cylindrical surface 11, the said ring-like element 1 is provided with cutaway portions 13 forming spring-receiving seats, and with correspondingly disposed enlargements or bosses, as 14, extending from the inner 90 cylindrical surface 15 of the said ring-like element 1. Extending from each cut-away portion or depression 13, through the body of the ring-like element 1, and each enlargement or boss 14, is a pin-receiving guide 100 or hole 16, the central axes of each pair of such guides or holes 16, located, respectively, upon the opposite sides of a spoke 7 being parallel to the main central axis of the said spoke. 105

Movably disposed within the above-mentioned annular space 12, with intervening spaces 17 between them, are a number of arc-shaped thread-blocks or elements 18, provided in their outer surfaces 19 with receiving 110 spaces 20 and upon their inner surfaces with correspondingly disposed cutaway or recessed

portions 21, also forming spring-receiving seats. Extending from each receiving space 20, through the body of the block or element 18, and into each cut-away or recessed portion 21 is a pin-receiving guide or hole 22, the respective guides or holes 22 being in alinement with the corresponding and previously mentioned guides or holes 16, as will be clearly evident from an inspection of

10 Fig. 1 of the drawings.

Seated in each pair of oppositely disposed spring-receiving seats 13 and 21 are the respective ends of coiled springs 23, and mounted in the corresponding and alined 15 guides or holes 16 and 22 and extending into and through the said coiled springs 23 are suitable pins 24, in the form of bolts, each bolt having its head 25 resting in a depression 20 and having its nut 26 screwed upon 20 the screw-threaded end-portion of the bolt with the nut 26 thereon resting upon an enlargement or boss 14. In this manner, the springs 23 can be brought under proper tension, and also, proper adjustment may be 25 made, so that the various tread-blocks or elements 18 may be correctly positioned. Each tread-block or element 18 is further provided in its outer face with a receiving depression or pocket, as 27, in which is suitably secured in any manner, as by means 30 of screws 28, suitable cushioning elements 29 made of rubber or other analogous material.

From the foregoing description of the 35 present invention, and from an inspection of the accompanying drawings, it will be evident that I have provided a simple, cheap, durable, and perfectly operating construction, and due to the movable arrangement 40 of the several tread-blocks or elements, the resiliency of the wheel is retained, while the wearing qualities are enhanced.

I claim:—

1. A vehicle-wheel comprising a ring-like element, and circular side-members, said members extending beyond the outer cylindrical surface of said ring-like element to provide an outer annular receiving space, said ring-like element being formed with 45 peripheral depressions providing spring-receiving seats, and pin-receiving guides ex-

tending from said seats through said ring-like element, a plurality of arc-shaped tread-blocks movably disposed between the side-members of said ring-shaped element, said blocks being also formed with depressions providing spring-receiving seats, and pin-receiving guides in alinement with the guides in said ring-like element, a pin disposed in each pair of oppositely disposed receiving guides, a spring encircling each pin, the respective ends of each spring being seated upon the respective oppositely placed spring-receiving seats, and means upon each pin for bringing said springs under tension and correctly positioning said tread-blocks.

2. A vehicle-wheel comprising a ring-like element, and circular side-members, said members extending beyond the outer cylindrical surface of said ring-like element to provide an outer annular receiving space, said ring-like element being formed with peripheral depressions providing spring-receiving seats, and pin-receiving guides extending from said seats through said ring-like element, a plurality of arc-shaped tread-blocks movably disposed between the side-members of said ring-shaped element, said blocks being formed in their inner surfaces 75 with depressions providing spring-receiving seats, and pin-receiving guides in alinement with the guides in said ring-like element, said blocks being also provided in their outer surfaces with depressions, a pin disposed in each pair of oppositely disposed receiving guides, and a head upon each pin resting in one of said last-mentioned depressions, a spring encircling each pin, the respective ends of each spring being seated 80 upon the respective oppositely placed spring-receiving seats, and means upon each pin for bringing said springs under tension and correctly positioning said tread-blocks.

In testimony whereof, that I claim the invention set forth above I have hereunto set my hand this 2nd day of March, 1917.

GEORGE W. CONWAY.
